US00D582882S

(12) **United States Design Patent**
Kim et al.

(10) **Patent No.:** **US D582,882 S**
(45) **Date of Patent:** **** Dec. 16, 2008**

(54) **PORTABLE PHONE**

(75) Inventors: **Dong-Kyun Kim**, Seoul (KR);
Joon-Suh Kim, Anyang-Si (KR);
Gee-Hong Yoon, Seongnam-Si (KR)

(73) Assignee: **Samsung Electronics Co., Ltd.**,
Suwon-Si (KR)

(**) Term: **14 Years**

(21) Appl. No.: **29/300,329**

(22) Filed: **Mar. 14, 2008**

(30) **Foreign Application Priority Data**

Dec. 28, 2007 (KR) 30-2007-0053994

(51) **LOC (8) Cl.** **14-03**

(52) **U.S. Cl.** ..... **D14/138 AD**
